CLAIM

The ornamental design for a beverage container, as shown and described.

DESCRIPTION

FIG. 1 is a top, front perspective view of a first embodiment of a beverage container showing our new design;

FIG. 2 is a front elevational view thereof, shown at a reduced scale;

FIG. 3 is a rear elevational view thereof;

FIG. 4 is a left side elevational view thereof;

FIG. 5 is a right side elevational view thereof;

FIG. 6 is a top plan view thereof;

FIG. 7 is a top, front perspective view of a second embodiment of a beverage container showing our new design;

FIG. 8 is a front elevational view thereof, shown at a reduced scale;

FIG. 9 is a rear elevational view thereof;

FIG. 10 is a left side elevational view thereof;

FIG. 11 is a right side elevational view thereof; and,

FIG. 12 is a top plan view thereof.

The oblique shade lines shown in drawing FIGS. 1-6 represents a reflective surface.

The stipple shading shown in FIG. 7-12 drawing represents a contrasting textured surface.

The broken lines shown in the drawings are included for the purpose of illustrating environmental structure that forms no part of the claimed design.
